UNITED STATES PATENT OFFICE

HENRY B. GORMAN, OF LYNCHBURG, VIRGINIA, ASSIGNOR TO UNITED SHOE MACHINERY CORPORATION, OF PATERSON, NEW JERSEY, A CORPORATION OF NEW JERSEY

INSOLE

Original application filed May 17, 1927, Serial No. 192,037. Divided and this application filed June 13, 1929. Serial No. 370,585.

This invention relates to insoles for use in the manufacture of shoes of the types in which an upper is lasted over upon an insole and secured thereto in lasted position and particularly to insoles provided with projections to which the upper may be secured in lasted position, for example, by staples, an outsole being applied to the shoe in contact with the overlasted upper. Insoles of this type are disclosed in United States Letter Patent No. 1,744,759, granted Jan. 28, 1930, on my prior application of which this application is a division.

Objects of the invention are to provide an improved insole to which the upper may be attached by metallic fastenings without any liability of the fastenings appearing on the inner face of the insole, to provide an insole the outer surface of which, after attachment of the upper, will be smooth and substantially unbroken, as well as to provide an insole which will be convenient to use and cheap to manufacture.

As herein illustrated, the invention provides an insole comprising two layers of material which are coexpensive with the last bottom, the outer layer having cuts extending through it and providing flaps which may be readily raised so that a clinching tool may be placed beneath the raised portions to clinch against the lower face of the outer layer a fastening driven through the upper and the outer layer.

In the illustrated form of the invention, the outer layer is slit longitudinally of the insole from the tip line to the breast line, thereby providing two flaps to which the upper may be secured in the lasting operation, the fastenings being clinched on the under sides of the flaps by a clinching tool placed beneath them. If the upper is progressively lasted, the clinching tool may be moved along the slit in position to clinch successive fastenings driven through the upper and the flap. After lasting, the flaps are laid down smoothly in their original position against the inner layer of the insole. In order that the portions of the flaps near the ends of the shoe may be raised more freely, transverse

slits through the outer layer along the tip line and breast line may be provided.

In lasting the toe and heel ends of shoes, of which the illustrated through-and-through sewed shoe furnishes an example, the upper materials are frequently lasted over the bottom of the insole and secured by tacks which are driven through the upper and the insole and clinched by iron plates on the ends of the last. Accordingly, the lasting flaps, as illustrated, do not extend beyond the tip line and breast line. It is to be understood, however, that the flaps may be continued toward the ends of the insole so that the ends of the shoe may be lasted in the same way as the sides.

Other features of the invention will appear more fully from the following description when read in connection with the accompanying drawing and will be pointed out in the claims.

Although the invention has been illustrated as embodied in a shoe in which the outsole is attached by through-and-through stitching, it is to be understood that, in its broader aspects, the invention is not limited to this manner of attaching the outsole.

In the drawing,

Fig. 1 is a perspective view of an insole showing a form of the invention; and

Fig. 2 is a transverse section of a shoe having an insole of the form shown in Fig. 1.

Insoles embodying the present invention are preferably of sheet-material, such as buckram, canvas or split leather, the illustrated material being frictioned canvas of such weight that two thicknesses of it will provide the desired strength and flexibility for the insole. Thus the insole illustrated in Fig. 1 consists of two adhesively connected pieces of sole-shaped frictioned canvas 4 and 6, one overlying the other. An advantage of employing frictioned canvas is that the two layers comprising the insole may be caused to adhere simply by being pressed together. It should be understood, however, that for either or both of the layers 4 and 6, material other than frictioned canvas may be substituted, and other means of securing the insole layers together may be employed. Conven-

iently, although not necessarily, the pieces 4 and 6 are died out or otherwise cut to insole shape before one is placed on the other. The layer 4, which constitutes the outer layer of the insole, has a longitudinal slit 8 and transverse cuts at the breast line 10 and at the tip line 12, preferably made prior to the fastening of the two layers together and forming flaps 14 and 16. Preferably the layers 4 and 6 are attached to each other only along the marginal portions between the tip line and the breast line, that is outside of the dotted lines shown at 18 in Fig. 1, and such attachment is preferably made by the use of cement, although, of course, stitching along the lines 18 may be employed if desired. The width of the margin 24 of the insole between the attached edge of the flap and the edge of the insole is sufficient to permit an outsole to be applied to the overlasted portion of an upper as shown in Fig. 2 and secured to the shoe in any desired manner, for example, by stitches passing through the outsole or a portion thereof, through the upper and through the margin 24 of the insole.

In use, the insole is placed upon the bottom of a last with the face having the flaps 14 and 16 outermost, the two layers of the insole being coextensive with the last bottom. An upper 28 is placed upon the last and lasted over the margin 18 of the insole, each successive portion of the upper being secured preferably by a staple 26 driven through the upper and one of the flaps, and clinched on the under side of the flap. The flaps may be raised prior to the lasting operation and if not are readily raised in the stapling operation by the anvil or channel guide of the stapling machine. The anvil of a staple lasting machine is passed through the slit 8 beneath the part 14 or the part 16, according to which side of the shoe is being lasted, and in the operation of the machine the upper is drawn over the insole and a staple driven through the upper and one of the portions 14, 16 of the insole, the staple being clinched by the anvil on the under face of the outer layer. The machine employed may be of the type disclosed in an application Serial No. 138,300 filed Sept. 28, 1926 by George Goddu. In the use of this machine successive portions of the upper are tensioned by a gripper, and, while control of the upper is maintained by a staple nozzle, a staple is inserted through a tensioned portion of the upper and one of the flaps 14, 16, the staple being clinched by a channel guide or anvil disposed against the under side of the flap. After the lasting has been effected by securing tensioned portions thereof to each of the flaps at the two sides of the shoe, the flaps are pressed back into the recesses from which they were cut, leaving the bottom of the insole perfectly flat and substantially unbroken. Filling material may be dispensed with, or

at most, only enough filler inserted to compensate for the thickness of the margin of the overlasted upper. At the toe and heel the upper may be lasted, for example, on a bed type of lasting machine, and tacks driven through the upper and completely through the insole, their points being clinched by the metal plates with which the toe and heel ends of the last are provided. An outsole is then applied to the shoe in any usual manner, as illustrated, the last is removed, and the outsole, upper and insole secured together by through-and-through stitches 22 passing through the margin 18 of the insole outside of the line of the staples 26.

Having thus described my invention, what I claim as new and desire to secure by Letters Patent of the United States is:

1. An insole for shoes comprising a plurality of layers attached together at their margins, one of the layers being slit longitudinally of the sole to permit the insertion of a tool beneath said layer for clinching fastenings driven through the upper and the layer.

2. An insole for shoes comprising a plurality of layers attached together at their margins, the inner layer being intact and the outer layer being slit longitudinally of the sole to permit the insertion of a tool beneath said layer for clinching fastenings to hold the upper to the outer face of said layer.

3. An insole comprising a plurality of similar layers secured together at their margins, the outer layer being cut through longitudinally of the insole to permit the insertion of a clinching tool for clinching fastenings driven through the upper and the outer layer adjacent to the margin of the insole.

4. An insole for shoes comprising a plurality of layers attached together at their margins, one of the layers being slit centrally longitudinally of the sole to permit the insertion of a tool for clinching the fastenings by which the upper is held to the insole.

5. An insole for shoes comprising two layers, the outer layer being cut longitudinally from the breast line to the tip line and having transverse cuts at the tip line and the breast line whereby the outer layer may be raised to permit the insertion of a tool for clinching fastenings by which the lasted upper is held to the insole.

In testimony whereof I have signed my name to this specification.

HENRY B. GORMAN.
